[57] ABSTRACT

A synchronous buffer unit module which includes a shift register, a bookkeeping register and two clock pulse selectors. An internal clock pulse generator operates at a frequency n times the average frequency of information input and information output devices. The shift register contains n stages each controlled by an output of the bookkeeping register. During the period when information is stored in the shift register the bookkeeping register is controlled selectively either by a combination of the internal clock pulses and the clock pulses of an external information source through one of the clock pulse selectors, or in the case where the unit forms a buffer stage subsequent to the first buffer stage of a buffer assembly by pulses from the last stage of the bookkeeping register in a preceding buffer unit. During the output period of the buffer unit the bookkeeping stage is controlled through a second clock pulse selector by the internally generated clock pulses and the clock pulses from an external unit to which the information in the buffer is to be transmitted or, in the case where the unit precedes the last unit in a buffer assembly of such buffer units, by a signal derived from the first stage of a bookkeeping memory in the next subsequent buffer unit.

**MODULAR SYNCHRONOUS BUFFER UNIT FOR A
BUFFER HAVING A CAPACITY DEPENDING ON
THE NUMBER OF INTERCONNECTED
IDENTICAL BUFFER UNITS**

The invention relates to a synchronous buffer unit comprising a register composed of a plurality of sections. The register is coupled to an information input and output terminal for supplying information to the buffer unit and for transmitting information from the buffer unit. The information is temporarily stored in the register. The information has a given clock pulse frequency. Supply terminals are provided for supplying the clock pulses of the information to be written in or read out of the buffer.

A synchronous buffer unit of this kind, where the information supplied to the input terminal is serially written in the consecutive sections of the register and the information is serially read from the consecutive sections and applied to the information output terminal, is generally known and is used inter alia for coupling digital telephone and data transmission systems. These transmission systems operate at clock pulse frequencies which are equal on the average, but which may be unequal at any given instant due to the occurrence of phase variations, caused, for example, by delay time variations in the transmission systems.

The known buffer unit is provided with selection units and counters for writing information in and reading information out of the consecutive sections of the register. These selection devices and counters successively connect, under the control of clock pulses of the information to be written in or read out, the information input terminal or output terminal, respectively, to the consecutive sections of the register. These selection units and counters are rather bulky. This is particularly so if the difference of the clock pulse frequencies of the transmission systems between which the buffer unit is provided may be large at any given instant. In that case a buffer unit having a large storage capacity is required, i.e., a buffer unit comprising a register having a large number of sections, the selection units and the counters thereof being accordingly bulky.

One object of the invention is to provide a buffer unit which is less bulky, in particular in the case of a large storage capacity, and which can be readily realized for achieving a large storage capacity by series connection of two or more buffer units having a smaller storage capacity. Another object of the invention is to realize a buffer unit having a structure of a frequently recurrent nature, so that the buffer unit can be assembled mainly from one kind of logical component.

The unit according to the invention is characterized in that the register is a shift register, each section of which is provided with a control terminal for supplying shift pulses, and a series of bistable elements is provided, the bistable elements and the sections of the shift register being associated with each other in a one-to-one relationship. Each bistable element is provided with two signal inputs, one clock pulse input and two signal outputs, which are inverse to each other. The clock pulse inputs of which are connected to a clock pulse connection terminal for supplying thereto clock pulses having a clock pulse repetition frequency which amounts to more than double the clock pulse frequency of the information to be written in or read out. A first clock pulse selector is coupled to the clock pulse connection terminal, and the supply terminal for the

clock pulses of the information to be written in, and a signal input of the first bistable element of the said series for the non-recurrent setting of the first bistable element of the said series within each clock pulse period of the information to be written in. A signal output of each bistable element is connected to a signal input of the subsequent bistable element for setting, under the control of the clock pulses applied to the clock pulse connection terminals, the said non-set subsequent bistable element when the said each bistable element has been set. The other signal input of each bistable element is connected to the other signal output of the subsequent bistable element for resetting the said set each bistable element when the said subsequent bistable element is in the reset state. The said other signal output of each bistable element is also connected to the control terminal of the associated section of the shift register so as to supply thereto a shift pulse when the bistable element is set. A second pulse selector is coupled to the clock pulse connection terminal, and to the information supply terminal for the clock pulses of the information to be read out, and the said other signal input of the last bistable element of the said series for the non-recurrent resetting of the last bistable element of the said series within each clock pulse period of the information to be read out.

In this context it is also to be noted that an asynchronous buffer unit is known which also uses a shift register for the temporary storage of information. These units are, however, less reliable as they impose requirements as regards the pulse duration of the clock pulses of the information to be written in and read out, respectively.

BRIEF DESCRIPTION OF THE DRAWING

In order that the invention may be readily carried into effect, some embodiments thereof will now be described in detail, by way of example, with reference to the accompanying diagrammatic drawings, in which:

FIG. 1 shows an embodiment of a buffer unit according to the invention.

FIG. 2a is a detailed view of a clock pulse selector of the buffer unit according to the embodiment shown in FIG. 1.

FIG. 2b shows a graph of the signals occurring in the clock pulse selector shown in FIG. 2a.

FIG. 3 shows an embodiment of two series-connected buffer units according to FIG. 1.

**DESCRIPTION OF THE PREFERRED
EMBODIMENT**

The unit shown in FIG. 1 comprises a register R_1 which is comprised of, for example, n sections F_1 to F_n , said register R_1 being provided with information input terminals p_1 and p_2 and information output terminals p_3 and p_4 . The sections F_1 to F_n are formed by bistable elements which are used for the temporary storage of information. For writing information in or reading information from these sections, a known unit comprises two selection networks and two counters. A first selection network is connected between the information input terminals p_1 and p_2 and the inputs of the sections F_1 to F_n . Under the control of the clock pulses of the information to be written in, the first selection network connects C_{Si} , by means of a first counter and the information input terminals p_1 and p_2 , successively to the input terminals of the consecutive sections F_1 to F_n of

the register R_1 . The counter stores the identity of the section in which the last information has been written. After having reached the highest counting position, this counter always returns to its starting position, after which the register R_1 is written in again. The second selection network is connected between the outputs of the sections F_1 to F_n and the information outputs p_3 and p_4 . Under the control of the clock pulses of the information C_u to be read out, this selection network successively connects the information output terminals p_3 and p_4 to the output terminals of the consecutive sections F_1 to F_n of the register R_1 by means of the second counter. The second counter stores the identity of the section from which the last information has been read. This counter also returns to the starting position after reaching its highest counting position. As the register R_1 comprises n sections, the largest phase difference which can occur between information to be written in and information to be read out corresponds to n clock pulse periods.

In transmission systems in which the phase difference between the information to be written in and read out can be very large at any given instant, a register having a large number of sections is to be used, and hence the selection networks and the counters are large, which results in a bulky buffer unit.

The concept of the unit according to the invention essentially differs from this known device in that the register R_1 is a shift register. In addition each section F_1 to F_n of the shift register is provided with a control terminal T for supplying shift pulses thereto. A series R_2 of bistable elements F_1' to F_n' is provided. The bistable elements F_1' to F_n' and the sections F_1 to F_n of the shift register R_1 associated with each other in a one-to-one relationship. Each of said bistable elements is provided with two signal inputs J and K , respectively, one clock pulse input T and two signal outputs Q and $\bar{Q}$, respectively, which are inverse to each other. The clock pulse inputs T are connected to a clock pulse connection terminal CL for supplying thereto clock pulses c_1 , having a clock pulse repetition frequency f_{cl} amounting to more than double the clock pulse frequency of the information to be written in or read out. A first clock pulse selector C_{s1} is coupled to the clock pulse connection terminal CL , and the supply terminal for the clock pulses of the information C_1 to be written in, and a signal input J of the first bistable element F_1' of the said series for the non-recurrent setting of the first bistable element F_1' of the said series within each clock pulse period of the information to be written in signal output Q of each bistable element F_1' to F_{n-1}' is connected to a signal input J of the subsequent bistable element F_2' to F_n' for setting, under the control of the clock pulses c_1 , the said non-set subsequent bistable element F_2' to F_n' when the said each bistable element F_1' to F_{n-1}' has been set. The other signal input $\bar{Q}$ of each bistable element F_1' to F_{n-1}' is connected to the other signal output K of the subsequent bistable element F_2' to F_n' for resetting each bistable element F_1' to F_{n-1}' when the said subsequent bistable element F_2' to F_n' is in the reset state. The other signal output $\bar{Q}$ of each bistable element F_1' to F_n' also is connected to the control terminal T of the associated section F_1 to F_n of the shift register R_1 for supplying thereto a shift pulse when the bistable element F_1' to F_n' has been set. A second clock pulse selector C_{s2} is coupled to the clock pulse connection terminal CL and to the supply

terminal C_u for the clock pulses of the information to be read out, and the said other signal input K of the last bistable element F_n' of the said series for the nonrecurrent resetting of the last bistable element F_n' of the said series within each clock pulse period of the information to be read out.

The sections F_1 to F_n of the shift register R_1 as well as the bistable elements F_1' to F_n' of the series R_2 shown in FIG. 1, are constructed as master-slave storage elements of the J-K type having information inputs J and K , a control pulse input T and also information outputs Q and $\bar{Q}$ which are inverse with respect to each other. The contents of each storage element are characterized in the set state by the logical value "1" and by the logical value "0" of the information output Q in the reset state.

As is known, the contents of the said master-slave storage element are determined, after the appearance of the control pulse on the control pulse input T , by the logical values of the information inputs J and K and the information output Q prior to the appearance of a control pulse.

Prior to the appearance of a control pulse, the logical values of the information inputs J and K and the information output Q of an element F_g can be mathematically represented by $J_{g,t}$, $K_{g,t}$, $Q_{g,t}$, respectively. The logical values of the information output Q of an element F_g after the appearance of a control pulse can be mathematically represented by $Q_{g,t+d}$. The relation between $Q_{g,t+d}$, $J_{g,t}$, $K_{g,t}$ and $Q_{g,t}$ of a master-slave storage element of the J-K type can be represented by the boolean expression

$$Q_{g,t+d} = Q_{g,t} \bar{K}_{g,t} + \bar{Q}_{g,t} J_{g,t} \quad (1)$$

In order to obtain a shift register which is used for the temporary storage of information, the information output Q_{g-1} of a section F_{g-1} ($g=2, \dots, n$) is interconnected in known manner to the information input J_g of the subsequent section F_g and the information output Q_{g-1} is interconnected to the information input K_g of the subsequent section F_g .

It results that:

$$J_{g,t} = Q_{g-1,t} \quad (2)$$

and

$$K_{g,t} = \bar{Q}_{g-1,t} \quad (3)$$

The logical values of the information output Q_g after the appearance of a control pulse can, therefore, be expressed in the logical values of the information outputs Q_g , Q_{g-1} and $\bar{Q}_g$ prior to the appearance of a control pulse, so

$$Q_{g,t+d} = Q_{g,t} Q_{g-1,t} + \bar{Q}_{g,t} \bar{Q}_{g-1,t} \quad (4)$$

It follows that, if the value of the information output $Q_{g-1,t} = "1"$ or $Q_{g-1,t} = "0"$, respectively, the value of the information output $Q_{g,t+d}$ will be "1" or "0", respectively, independent of the value of $Q_{g,t}$. Consequently, the information present on the information output Q_{g-1} prior to the appearance of the control

pulse will be present on the information output Q_o after the appearance of the control pulse. Consequently, the register R_1 is a shift register. As a result, the information received on the information input terminals p_1 and p_2 will be shifted through to the information output terminals p_3 and p_4 under the control of control pulses applied to control terminals T of the bistable elements F_1 to F_n .

In order to ensure that the shift register R_1 acts as a store for the buffer unit B, the information present on the information input terminals p_1 and p_2 is to be written in in the rhythm of the clock pulse frequency of the received information, and the information which is present in section F_n is to be read out of the clock pulse frequency of the transmission system to be connected. Moreover, it is to be avoided that information present in section F_n of the shift register R_1 is destroyed by the information stored in the preceding section F_{n-1} .

For this purpose the clock pulse detectors C_{11} and C_{12} , a series R_2 of bistable elements F_1' to F_n' and the clock pulse connection terminal CL are provided. The series R_2 of bistable elements F_1' to F_n' is used as a bookkeeping register for registering the sections of the shift register R_1 in which information is stored. By means of the sections of the shift register R_1 which are registered in the bookkeeping register and which contain information, the flow of information in the shift register R_1 is controlled at the clock instants of the clock pulses c_{11} .

The bistable elements F_1' to F_n' of the series R_2 are associated with the bistable elements F_1 to F_n of the shift register R_1 , and are also constructed as master-slave storage elements of the J-K type. For the purpose of distinction with respect to the J-K storage elements F_1 to F_n of the shift register R_1 , the inputs, outputs and the control pulse input of the J-K storage elements F_1' to F_n' of the series R_2 are referred to as signal inputs, signal outputs and clock pulse input.

The clock pulse input T of the bistable elements F_1' to F_n' are connected to the clock pulse connection terminal CL .

The signal outputs Q of the bistable elements F_1' to F_{n-1}' are connected to the signal inputs J of the elements F_2' to F_n' . The signal outputs $\bar{Q}$ of the elements F_2' to F_n' are connected to the signal inputs K of the elements F_1' to F_{n-1}' , so that for an element F_o' :

$$J_{o,t} = Q_{o-1,t} \quad (5)$$

$$K_{o,t} = \bar{Q}_{o+1,t} \quad (6)$$

The logical value of the signal output Q_o after the appearance of a clock pulse on the clock pulse input T can be expressed, using (1), (5) and (6), in the logical values of the signal outputs Q_o , Q_{o-1} and Q_{o+1} prior to the appearance of a clock pulse, so that

$$Q_{o,t+d} = Q_{o,t} Q_{o+1,t} + \bar{Q}_{o,t} Q_{o-1,t} \quad (7)$$

It follows that when the value of $Q_{o,t} = "0"$ and hence the value of $\bar{Q}_{o,t} = "1"$, the value of $Q_{o,t+d}$ is determined exclusively by the value of $Q_{o-1,t}$. The value "0" of Q_o will change to a value "1" after the appearance of a clock pulse only if Q_{o-1} has the value "1." This means that the value "1" of a storage element is shifted through to the next storage element only if the next

storage element has the value "0." In an analogous manner, the value "1" of Q_o after the appearance of a clock pulse changes to the value "0" only if Q_{o+1} has the value "0," i.e., the value "1" of a storage element is changed to the value "0" if the subsequent storage element has the value zero.

As is shown in FIG. 1, the signal outputs $\bar{Q}$ of the bistable elements F_1' to F_n' of the series R_2 are connected to the control pulse inputs T of the sections F_1 to F_n of the shift register R_1 . In order to write information into the first section F_1 of the shift register R_1 , the associated bistable element F_1' of the series R_2 is set to the set-state "1," as will be described hereinafter. As a result, a positive going edge appears on output terminal Q , and a negative going edge appears on output terminal $\bar{Q}$. As already described, the bistable elements of the sections F_1 to F_n are constructed so that at the trailing edge of the pulses applied to the control terminals T these elements are set in accordance with the signal values applied to the input terminals J and K , such that the information present on the information input terminals p_1 and p_2 is taken over by bistable element F_1 . As the bistable element F_1' is in the "1"-state, the next clock pulse c_{11} will set the bistable element F_2' to the next "1"-state, if the bistable element F_2' is in the "0"-state. The information present in section F_1 is written in section F_2 of the shift register R_1 by the trailing edge which is supplied by the bistable element F_2' to the control pulse input T of the section F_2 of the shift register R_1 via the signal output $\bar{Q}$. The subsequently appearing pulse shifts the information from section F_2 to F_3 etc. in an identical manner. This shifting through of information at clock pulse instants continues for as long as the subsequent section of the shift register R_1 does not contain information. This is to say, as long as the bistable element of the series R_2 associated therewith is in the "0"-state. However, if the subsequent bistable element of the series R_2 is in the "1"-state, the "1"-state of the relevant element will not be shifted through, as described above, upon the next clock pulse, and no control pulse will appear on the control pulse input T of the subsequent section of the shift register.

In this manner it is achieved that, starting from a shift register which does not contain information, the first information bit written in passes through the shift register and is stored in section F_n , the second information bit is stored in section F_{n-1} , etc.

By setting the bistable element F_n' to the "0"-state simultaneously with the reading out of information stored in the last section F_n of the shift register R_1 , as will be described hereinafter, the information from the last section but one F_{n-1} will be shifted to the last section F_n of the shift register by the first clock pulse appearing. The next clock pulse will shift the information from section F_{n-2} to section F_{n-1} , etc.

The speed at which an information bit is shifted through the shift register R_1 as long as no information is present in the subsequent section, is equal to the clock pulse frequency of the clock pulses applied to the clock pulse connection terminal CL .

Due to the fact that the shifting of information under the control of the clock pulses c_{11} applied to the clock pulse connection terminal CL requires a given period of time, a given minimum storage capacity of the buffer unit B exists which is larger than zero. Assuming that, when information is continuously written in the shift register R each information bit reaching section F_{n-1}

can be written directly in the last section F_n of the shift register R_1 ,

$$(f_{in}/f_{CL}) \times n \text{ bits} \quad (7)$$

rounded off to an integral number, are still present in the shift register. Therein, f_{in} represents the clock frequency of the information to be written in, and f_{CL} represents the clock frequency of the clock pulses c_l applied to the clock pulse connection terminal CL. This storage capacity is the minimum storage capacity of the buffer unit B.

If it is assumed that, when information is continuously read out of the shift register R_1 , each time when the first section F_1 of the shift register R_1 is written in this information cannot be applied directly to F_2 , the maximum storage capacity of the buffer unit is reached. This maximum storage capacity amounts to

$$(1 - f_u/f_{CL}) n \text{ bits} \quad (8)$$

, rounded off to an integral number, where f_u is the clock pulse frequency of the information to be read out. As the free store location arising when information is read from the last section F_n of the shift register R_1 requires a given period of time for being shifted back to the first section F_1 , this maximum storage capacity is smaller than the storage capacities corresponding to the total number of sections n of the shift register R_1 .

The maximum variation of the storage capacity of the buffer unit B is the difference between the maximum and the minimum storage capacity, which amounts to the value of

$$(1 - f_{in} + f_u/f_{CL}) \cdot n \text{ bits} \quad (9)$$

, rounded off to an integral number. As f_{in} is approximately equal to f_u , this becomes

$$(1 - 2f_{in}/f_{CL}) \cdot n \text{ bits.} \quad (10)$$

For a buffer unit which was realized in practice and which comprises a shift register having 100 sections, where $f_{in} = f_u = 2 \text{ MHz}$ was chosen, the storage capacity of 10 MHz, and 80 bits at a clock pulse frequency f_{CL} of 20 MHz. This demonstrates that the clock pulse frequency f_{CL} of the clock pulses c_l should preferably amount to 5 to 10 times the clock frequency of the information to be buffered.

In order to ensure that during the time that an information bit is present on the information input terminals p_1, p_2 of the shift register R_1 , the bistable element F_1' is set once to the position "1" for at the most one clock pulse period of the clock pulse frequency f_{CL} or, immediately after the instant that an information is read from the information output terminals p_3 and p_4 of the shift register R_1 , the bistable element F_n' is set once to the position "0" for at the most one clock pulse period of the clock pulse frequency f_{CL} , clock pulse selectors C_{s1} and C_{s2} are provided as is shown in FIG. 1. These clock pulse selectors C_{s1} and C_{s2} have a supply terminal c_1 and c_2 , respectively, for receiving the clock pulses of the information to be written in and read out, respectively, and are connected to the clock pulse connection terminal

CL for supplying clock pulses c_l thereto, and to an output terminal d_1 and d_2 , respectively. The diagram of a clock pulse selector of this kind is shown in FIG. 2a and is denoted by C_s . The clock pulses of the information to be written in or read out are applied to the terminal c and clock pulses c_l are applied to the terminal CL. The terminal CL is connected to the control terminal T of a J-K flipflop F. As is known and as can be readily verified by means of (1), when the values "1" and "0" are applied to the inputs J and K of a J-K flipflop, the value of the output Q becomes "1," independent of the value of Q prior to the appearance of a clock pulse on control terminal T, after the appearance of a clock pulse. Analogously, the value of the output Q becomes "0" after the appearance of a clock pulse when the values "0" and "1" are applied to the inputs J and K, independent of the value of Q prior to the appearance of a clock pulse. This property of a J-K flipflop is used to derive a pulse having a duration which is equal to one pulse period of the clock pulses c_l from each pulse of the pulse sequence applied to terminal c. For applying the desired signal values of the input terminals J and K of the J-K flipflop F, the clock pulse selector C_s comprises an AND-gate E_1 and a flipflop FF. The flipflop FF comprises two NAND-gates E_2 and E_3 , respectively, the outputs U and $\bar{U}$, respectively, of which are connected to one of the inputs of the NAND-gates E_3 and E_2 , respectively. The output $\bar{U}$, connected to an input of the AND-gate E_1 , determines whether the pulses applied to the input terminal c are applied to the input J of the J-K flipflop F. For this purpose, the terminal c is connected to the other input of the AND-gate E_1 , said AND-gate E_1 being connected to the input J of the J-K flipflop F via conductor g. The output U of the flipflop FF is connected to the input K of the J-K flipflop F. The flipflop circuit FF is controlled on the one hand by the signal value of the output $\bar{Q}$ of the J-K flipflop F, the said terminal $\bar{Q}$ being connected to the other input of the NAND-gate E_2 for this purpose, and on the other hand by the pulses applied to terminal c, said terminal c being connected to the other input of the NAND-gate E_3 for this purpose. The operation of the selector C_s will be described in detail with reference to the graph shown in FIG. 2b. It is assumed that at an instant t_0 the output $\bar{U}$ of the flipflop FF and the output $\bar{Q}$ of the J-K flipflop F have the value "1." If a clock pulse of the information to be written in or read out is received on terminal c at instant t_1 , AND-gate E_1 , to both inputs of which a signal of the value "1" is then applied, will apply a signal of the value "1" to the input J of the J-K flipflop F. A signal of the value "0" is applied to the input K of the J-K flipflop F. During the positive period of a clock pulse, the master storage element of the J-K flipflop F is set, the clock pulse appearing at the instant t_2 as is shown in the figure. The slave storage element of the J-K flipflop F is set upon the appearance of the trailing edge of the clock pulse at the instant t_3 . The signal value of the output signal on the output terminal Q of the J-K flipflop F then becomes "1," so the value of the signal on the output $\bar{Q}$ becomes "0." The signal value variation on the output $\bar{Q}$ causes the flipflop FF to be changed over, so that the output U supplies a signal of the value "1" and the output $\bar{U}$ supplies a signal of the value "0." The signal of the value "0" of the output $\bar{U}$ blocks the AND-gate E_1 , so that the signal value "0" is applied to the input J of the J-K flipflop F. A signal of the value

"1" is applied to the input K of the J-K flipflop F via the output U. The next leading edge of the clock pulse signal occurring at the instant t_4 resets the master storage element and the trailing edge occurring at the instant t_5 resets the slave storage element. At this instant the signal value of the output Q of the J-K flipflop F becomes "0" and the signal value of the output $\bar{Q}$ becomes "1." The signal value "1" of the output $\bar{Q}$ has no effect on the state of the flipflop FF as the latter changes over only if an input changes over from the signal value "1" to "0." Consequently, the applied signal values "0" and "1" prevail on the inputs J and K of the J-K flipflop F, so that the next clock pulses appearing will not change the state of the J-K flipflop. The flipflop FF is reset only if the pulse on input terminal c returns to the signal value "0," as is the case at instant t_6 , via the other input of the NAND-gate E_3 . The AND-gate E_1 , however, continues to apply a signal value "0" to the input J of the J-K flipflop F because a signal of the value "0," originating from input terminal c, is applied to the other input. As a signal of the value "0" is applied to both input terminals J and K, the J-K flipflop F is fixed in the reset state as can be readily deduced from formula (1). The clock pulse selector C_s has returned to its starting position, as indicated at the instant t_0 , at the instant t_7 . As appears from the foregoing description, a pulse appears once on the output terminal which is connected to output Q of the J-K flipflop F after a pulse has been applied to the input c under the control of the subsequent clock pulse c_1 , the former pulse having a duration amounting to one period of the clock pulse c_1 as is required.

If a buffer unit having a very large storage capacity variation is required, it can be readily constructed by connecting various buffer units B in series as is shown in FIG. 3. For this purpose the OR-gates O_1 and O_2 are provided, as is shown in FIG. 1. The output d_1 of clock pulse selector C_{s1} and an input terminal i_1 are connected to the inputs of the OR-gate O_1 . The output terminal of this OR-gate is connected to the input J of the bistable element F_1' . The output d_n of the clock pulse selector C_{sn} and an output terminal b_2 are connected to the inputs of the OR-gate O_2 . Also provided are an input terminal b_1 which is connected to the $\bar{Q}$ output of bistable element F_1' , and an output terminal i_n which is connected to the Q output of element F_n' .

In the series connection of a first and a second buffer unit as shown in FIG. 3, all elements of the first buffer unit are denoted by an extra index 1 and the elements of the second buffer unit are denoted by an extra index 2. By connecting, as shown in FIG. 3, the information output terminals p_{31} and p_{41} of a shift register R_{11} , not shown to the information input terminals p_{12} and p_{22} of a shift register R_{12} not shown, one shift register R, not shown in the figure, is obtained having a storage capacity which is equal to the sum of the storage capacities of the shift register R_{11} and R_{12} . In order to obtain a bookkeeping register R' , not shown in the figure, for the shift register R, the output terminals i_{u1} of a bookkeeping register R_{21} not shown and terminals b_{21} are connected to the input terminals i_{12} of the bookkeeping register R_{21} not shown and terminal b_{12} .

The clock pulses of the information to be written in or read out are applied to the terminals c_{s1} and c_{s2} , respectively, of clock pulse selectors C_{s11} and C_{s22} not shown. No signals are applied to the terminals c_{u1} and c_{u2} of clock pulse selectors C_{u11} and C_{u22} not shown, so

that the outputs d_{12} and d_{n1} apply a signal of the value "0" to OR-gates O_{s1} and O_{s2} , respectively, not shown, so that the flow of signal values occurring in the bookkeeping register R' is not disturbed. The clock pulse connection terminals CL_1 and CL_2 are interconnected and connected to clock pulse connection terminals C_1 for applying clock pulse c_1 to the clock pulse inputs T of the bistable elements F' of bookkeeping registers R_{21} and R_{22} not shown.

- 10 It is to be noted that it is alternatively possible to buffer word-organized information. For this purpose, each section F of the shift register R, of the embodiment shown in FIG. 1 is provided with a number of J-K flipflops F, said number being equal to the number of bits per word of the word-organized information. The control terminals T of the bistable elements F_g ($g=1 \dots n$) of a section of the shift register R, are connected to the Q output of the bistable element F_g' associated with these sections F. In that case the input terminal c_1 of the clock pulse selector C_{s1} and the input terminal c_n of the clock pulse selector C_{sn} are to be supplied with pulse sequences which are derived from the word frequency of the information to be written in or read out.

What is claimed is:

- 25 1. A buffer unit module for a synchronous buffer assembly using a plurality of serially connected buffer units to convey information signals from an information source to an information receiver each operating at a slightly different frequency; comprising input terminal means for receiving information signals having a given frequency; first clock pulse terminal means for receiving information clock pulses at the frequency of the information signals; second clock pulse terminal means for receiving local clock pulses at n times the frequency of the information signals, where n is an integer greater than 1; third clock pulse terminal means for receiving clock pulses at the frequency of the information receiver; information signal output terminal means; a shift register comprising n serially connected clocked bistable multivibrators, each of the multivibrators having an information input, a clock input and an information output, each multivibrator providing an output signal on the information output thereof corresponding to the signal on the information input thereof in response to a pulse on the clock input thereof; means connecting the information input of the first multivibrator of the series to the input terminal means of the buffer unit; means connecting the information output of the last multivibrator of the series to the information output terminal means of the module; a bookkeeping register comprising n serially connected J-K flipflops, each J-K flipflop having a J input, a K input, a clock pulse input, a Q output and a $\bar{Q}$ output, the serial connection between flipflops of the bookkeeping register comprising means for connecting the Q output of each but the last J-K flipflop in the series to the J input of the next succeeding J-K flipflop in the series and means connecting the $\bar{Q}$ output of each but the first J-K flipflop in the series to the K input of the preceding J-K flipflop in the series; means connecting the $\bar{Q}$ output of each J-K flipflop in the bookkeeping register to the clock input of the corresponding bistable multivibrator in the shift register; first clock pulse selection means connected to the first and second clock pulse terminals of the unit for providing a single output pulse having a pulse width equal to 1 period of the local clock pulses in response to a pulse of the information clock pulses;
- 30 2. A buffer unit module according to claim 1, wherein the information signal output terminal means is a shift register comprising n serially connected clocked bistable multivibrators, each of the multivibrators having an information input, a clock input and an information output, each multivibrator providing an output signal on the information output thereof corresponding to the signal on the information input thereof in response to a pulse on the clock input thereof; means connecting the information input of the first multivibrator of the series to the input terminal means of the buffer unit; means connecting the information output of the last multivibrator of the series to the information output terminal means of the module; a bookkeeping register comprising n serially connected J-K flipflops, each J-K flipflop having a J input, a K input, a clock pulse input, a Q output and a $\bar{Q}$ output, the serial connection between flipflops of the bookkeeping register comprising means for connecting the Q output of each but the last J-K flipflop in the series to the J input of the next succeeding J-K flipflop in the series and means connecting the $\bar{Q}$ output of each but the first J-K flipflop in the series to the K input of the preceding J-K flipflop in the series; means connecting the $\bar{Q}$ output of each J-K flipflop in the bookkeeping register to the clock input of the corresponding bistable multivibrator in the shift register; first clock pulse selection means connected to the first and second clock pulse terminals of the unit for providing a single output pulse having a pulse width equal to 1 period of the local clock pulses in response to a pulse of the information clock pulses;
- 35 3. A buffer unit module according to claim 1, wherein the information signal output terminal means is a shift register comprising n serially connected clocked bistable multivibrators, each of the multivibrators having an information input, a clock input and an information output, each multivibrator providing an output signal on the information output thereof corresponding to the signal on the information input thereof in response to a pulse on the clock input thereof; means connecting the information input of the first multivibrator of the series to the input terminal means of the buffer unit; means connecting the information output of the last multivibrator of the series to the information output terminal means of the module; a bookkeeping register comprising n serially connected J-K flipflops, each J-K flipflop having a J input, a K input, a clock pulse input, a Q output and a $\bar{Q}$ output, the serial connection between flipflops of the bookkeeping register comprising means for connecting the Q output of each but the last J-K flipflop in the series to the J input of the next succeeding J-K flipflop in the series and means connecting the $\bar{Q}$ output of each but the first J-K flipflop in the series to the K input of the preceding J-K flipflop in the series; means connecting the $\bar{Q}$ output of each J-K flipflop in the bookkeeping register to the clock input of the corresponding bistable multivibrator in the shift register; first clock pulse selection means connected to the first and second clock pulse terminals of the unit for providing a single output pulse having a pulse width equal to 1 period of the local clock pulses in response to a pulse of the information clock pulses;
- 40 4. A buffer unit module according to claim 1, wherein the information signal output terminal means is a shift register comprising n serially connected clocked bistable multivibrators, each of the multivibrators having an information input, a clock input and an information output, each multivibrator providing an output signal on the information output thereof corresponding to the signal on the information input thereof in response to a pulse on the clock input thereof; means connecting the information input of the first multivibrator of the series to the input terminal means of the buffer unit; means connecting the information output of the last multivibrator of the series to the information output terminal means of the module; a bookkeeping register comprising n serially connected J-K flipflops, each J-K flipflop having a J input, a K input, a clock pulse input, a Q output and a $\bar{Q}$ output, the serial connection between flipflops of the bookkeeping register comprising means for connecting the Q output of each but the last J-K flipflop in the series to the J input of the next succeeding J-K flipflop in the series and means connecting the $\bar{Q}$ output of each but the first J-K flipflop in the series to the K input of the preceding J-K flipflop in the series; means connecting the $\bar{Q}$ output of each J-K flipflop in the bookkeeping register to the clock input of the corresponding bistable multivibrator in the shift register; first clock pulse selection means connected to the first and second clock pulse terminals of the unit for providing a single output pulse having a pulse width equal to 1 period of the local clock pulses in response to a pulse of the information clock pulses;
- 45 5. A buffer unit module according to claim 1, wherein the information signal output terminal means is a shift register comprising n serially connected clocked bistable multivibrators, each of the multivibrators having an information input, a clock input and an information output, each multivibrator providing an output signal on the information output thereof corresponding to the signal on the information input thereof in response to a pulse on the clock input thereof; means connecting the information input of the first multivibrator of the series to the input terminal means of the buffer unit; means connecting the information output of the last multivibrator of the series to the information output terminal means of the module; a bookkeeping register comprising n serially connected J-K flipflops, each J-K flipflop having a J input, a K input, a clock pulse input, a Q output and a $\bar{Q}$ output, the serial connection between flipflops of the bookkeeping register comprising means for connecting the Q output of each but the last J-K flipflop in the series to the J input of the next succeeding J-K flipflop in the series and means connecting the $\bar{Q}$ output of each but the first J-K flipflop in the series to the K input of the preceding J-K flipflop in the series; means connecting the $\bar{Q}$ output of each J-K flipflop in the bookkeeping register to the clock input of the corresponding bistable multivibrator in the shift register; first clock pulse selection means connected to the first and second clock pulse terminals of the unit for providing a single output pulse having a pulse width equal to 1 period of the local clock pulses in response to a pulse of the information clock pulses;
- 50 6. A buffer unit module according to claim 1, wherein the information signal output terminal means is a shift register comprising n serially connected clocked bistable multivibrators, each of the multivibrators having an information input, a clock input and an information output, each multivibrator providing an output signal on the information output thereof corresponding to the signal on the information input thereof in response to a pulse on the clock input thereof; means connecting the information input of the first multivibrator of the series to the input terminal means of the buffer unit; means connecting the information output of the last multivibrator of the series to the information output terminal means of the module; a bookkeeping register comprising n serially connected J-K flipflops, each J-K flipflop having a J input, a K input, a clock pulse input, a Q output and a $\bar{Q}$ output, the serial connection between flipflops of the bookkeeping register comprising means for connecting the Q output of each but the last J-K flipflop in the series to the J input of the next succeeding J-K flipflop in the series and means connecting the $\bar{Q}$ output of each but the first J-K flipflop in the series to the K input of the preceding J-K flipflop in the series; means connecting the $\bar{Q}$ output of each J-K flipflop in the bookkeeping register to the clock input of the corresponding bistable multivibrator in the shift register; first clock pulse selection means connected to the first and second clock pulse terminals of the unit for providing a single output pulse having a pulse width equal to 1 period of the local clock pulses in response to a pulse of the information clock pulses;
- 55 7. A buffer unit module according to claim 1, wherein the information signal output terminal means is a shift register comprising n serially connected clocked bistable multivibrators, each of the multivibrators having an information input, a clock input and an information output, each multivibrator providing an output signal on the information output thereof corresponding to the signal on the information input thereof in response to a pulse on the clock input thereof; means connecting the information input of the first multivibrator of the series to the input terminal means of the buffer unit; means connecting the information output of the last multivibrator of the series to the information output terminal means of the module; a bookkeeping register comprising n serially connected J-K flipflops, each J-K flipflop having a J input, a K input, a clock pulse input, a Q output and a $\bar{Q}$ output, the serial connection between flipflops of the bookkeeping register comprising means for connecting the Q output of each but the last J-K flipflop in the series to the J input of the next succeeding J-K flipflop in the series and means connecting the $\bar{Q}$ output of each but the first J-K flipflop in the series to the K input of the preceding J-K flipflop in the series; means connecting the $\bar{Q}$ output of each J-K flipflop in the bookkeeping register to the clock input of the corresponding bistable multivibrator in the shift register; first clock pulse selection means connected to the first and second clock pulse terminals of the unit for providing a single output pulse having a pulse width equal to 1 period of the local clock pulses in response to a pulse of the information clock pulses;
- 60 8. A buffer unit module according to claim 1, wherein the information signal output terminal means is a shift register comprising n serially connected clocked bistable multivibrators, each of the multivibrators having an information input, a clock input and an information output, each multivibrator providing an output signal on the information output thereof corresponding to the signal on the information input thereof in response to a pulse on the clock input thereof; means connecting the information input of the first multivibrator of the series to the input terminal means of the buffer unit; means connecting the information output of the last multivibrator of the series to the information output terminal means of the module; a bookkeeping register comprising n serially connected J-K flipflops, each J-K flipflop having a J input, a K input, a clock pulse input, a Q output and a $\bar{Q}$ output, the serial connection between flipflops of the bookkeeping register comprising means for connecting the Q output of each but the last J-K flipflop in the series to the J input of the next succeeding J-K flipflop in the series and means connecting the $\bar{Q}$ output of each but the first J-K flipflop in the series to the K input of the preceding J-K flipflop in the series; means connecting the $\bar{Q}$ output of each J-K flipflop in the bookkeeping register to the clock input of the corresponding bistable multivibrator in the shift register; first clock pulse selection means connected to the first and second clock pulse terminals of the unit for providing a single output pulse having a pulse width equal to 1 period of the local clock pulses in response to a pulse of the information clock pulses;
- 65 9. A buffer unit module according to claim 1, wherein the information signal output terminal means is a shift register comprising n serially connected clocked bistable multivibrators, each of the multivibrators having an information input, a clock input and an information output, each multivibrator providing an output signal on the information output thereof corresponding to the signal on the information input thereof in response to a pulse on the clock input thereof; means connecting the information input of the first multivibrator of the series to the input terminal means of the buffer unit; means connecting the information output of the last multivibrator of the series to the information output terminal means of the module; a bookkeeping register comprising n serially connected J-K flipflops, each J-K flipflop having a J input, a K input, a clock pulse input, a Q output and a $\bar{Q}$ output, the serial connection between flipflops of the bookkeeping register comprising means for connecting the Q output of each but the last J-K flipflop in the series to the J input of the next succeeding J-K flipflop in the series and means connecting the $\bar{Q}$ output of each but the first J-K flipflop in the series to the K input of the preceding J-K flipflop in the series; means connecting the $\bar{Q}$ output of each J-K flipflop in the bookkeeping register to the clock input of the corresponding bistable multivibrator in the shift register; first clock pulse selection means connected to the first and second clock pulse terminals of the unit for providing a single output pulse having a pulse width equal to 1 period of the local clock pulses in response to a pulse of the information clock pulses;

means connecting the output pulse of the first pulse selection means to the J input of the first J-K flipflop in the bookkeeping register; a second clock pulse selection means connected to the second and third clock pulse terminals of the unit for providing a single output pulse having a pulse width equal to 1 period of the local clock pulses in response to a pulse from the receiver clock pulses; an interunit bookkeeping input terminal; a first OR-gate having an output connected to the J input of the first J-K flipflop in the bookkeeping register; means connecting the output pulse of the first clock pulse selection means and the intermediate bookkeeping input terminal to the inputs of the first OR-gate, whereby the bookkeeping register receives input signals from the information clock pulse terminal through the first clock pulse selection means if the buffer unit is the first unit in the buffer assembly, and whereby the bookkeeping register receives input signals from the interunit bookkeeping input terminal if the buffer unit is connected to the information source through other buffer units; an interunit feedback out-

5 put terminal connected to the $\bar{Q}$ output of the first J-K flipflop in the bookkeeping register; an interunit feedback input terminal; a second OR-gate having an output connected to the K input of the last J-K flipflop in the bookkeeping register; means connecting the output pulse of the second clock pulse selection means and the interunit feedback input terminal to inputs of the second OR-gate, whereby the last stage of the bookkeeping register receives an input from the clock pulses of the information receiver through the second clock pulse selection means if the buffer unit in the buffer assembly is directly connected to the information receiver and whereby the last stage of the bookkeeping register receives an input from the interunit feedback input terminal if the buffer unit is connected to the information receiver through another buffer unit; and an interunit bookkeeping output terminal connected to the $\bar{Q}$ output of the last stage of the bookkeeping register.
